UNITED STATES PATENT OFFICE.

VICTOR R. DESPARD, OF HINSDALE, ILLINOIS, ASSIGNOR, BY MESNE ASSIGNMENTS, TO MCGILL MANUFACTURING COMPANY, OF VALPARAISO, INDIANA, A CORPORATION OF INDIANA.

LOCKING MEANS FOR SHELLS.

1,369,168.

Specification of Letters Patent. Patented Feb. 22, 1921.

Original application filed April 6, 1918, Serial No. 227,111. Divided and this application filed September 23, 1918. Serial No. 255,258.

To all whom it may concern:

Be it known that I, VICTOR R. DESPARD, a citizen of the United States, residing at Hinsdale, in the county of DuPage and State 5 of Illinois, have invented a certain new and useful Improvement in Locking Means for Shells, of which the following is a full, clear, concise, and exact description, reference being had to the accompanying drawings, forming a part of this specification.

My invention relates to locking means for shells, that is, for locking shells and caps together so as to hold the incandescent socket in position, an object being to provide an improved and simplified device of this character in which the cap and shell are securely held together under normal conditions but may be readily separated by manipulation when desired. One of the features of my invention is an improved form 20 of skirt on the cap and a coöoperating collapsible end on the shell whereby all the parts are securely held together. In this connection I have provided a conical circularly recessed skirt on the cap and a correspondingly formed shouldered portion at the end of the shell so that the shell may be inserted telescopically into the recess of the skirt where it is acted upon by a lug on 25 the interior of the skirt so as to lock the parts together.

The present application which is a division of my application Serial No. 227,111, filed Apr. 6, 1918, is directed more particularly to a device of the above character in which an adjustable lug is provided so that the cap and shell may be locked in any one of a number of different positions.

Referring now more particularly to several embodiments of my invention as illustrated in the accompanying drawing in which like reference characters indicate like parts:

Figure 1 is a side elevation of one form 45 of my invention showing the multiple position cap and shell assembled;

Fig. 2 shows the collapsible end of the shell;

Fig. 3 is a section along the line 3—3 of 50 Fig. 2;

Fig. 4 is a section along the line 4—4 of Fig. 1;

Fig. 5 is a transverse section along the line 5—5 of Fig. 4;

Fig. 6 is a view looking upwardly into 55 the interior of the cap removed from the shell;

Fig. 7 is a detail view of the adjustable lug carrying arm which is fitted inside the cap;

Fig. 8 is a detail view of the nipple which is staked in the cap;

Fig. 9 is a flanged collar which passes through the lug arm and is secured to the interior of the cap by the nipple.

Fig. 10 is a side elevation of another form 60 of my invention in which the shell and cap have but a single adjustment;

Fig. 11 is a section along the line 11—11 of Fig. 10;

Fig. 12 is a section along the line 12—12 of Fig. 11;

Fig. 13 is an interior view of the single position cap;

Fig. 14 is a perspective view of the single 75 position cap, and

Fig. 15 is a locking washer for the single position cap.

Referring now to the first form of my invention as shown in Figs. 1 to 9, it comprises 80 a shell 15 having the usual key slot 16 which

is preferably enlarged at 17 so that the side edges thereof may engage the outer edges of the locking lug hereinafter more fully referred to. The corners 18 of the slot are 85

pressed inwardly slightly so as to properly pass the socket key. The lower end of the shell 15 is provided with a roll thread adapted to receive a shade holder or similar device.

The upper end of the shell is provided with a conical shouldered flange 19 adapted to be telescopically inserted into a correspondingly formed skirt 20 of the cap 90

21, this skirt having its edge 22 drawn inwardly so as to form a shoulder and provide 95 a circular recess in the skirt. Thus when the shell is inserted in the cap, it first collapses and as the shoulder on the flange 19 of the shell passes the edge 22 on the skirt, the shell again expands and snaps into hold-

100

ing position in the cap. When thus assembled the shoulder 23 on the flange 19 abuts inside the inturned edge 22 of the skirt while the edge 24 of the flange 19 abuts the shoulder 25 of the skirt 20, the shell thus being firmly held against any rocking motion. The construction as thus far described would permit of a ready separation of the cap and shell by a longitudinal pull on the parts.

10 That is, unless something is provided to prevent a normal collapse of the shell it may be readily withdrawn from the cap. But, in order to prevent such a separation of the parts, I provide a locking lug 26 which is carried within the cap and acts upon the edges 17 of the key slot, this lug in the form of my invention shown in Figs. 1 to 9 being an adjustable lug 26 carried by a lug carrying arm or yoke 27, rotatably mounted within the cap and securely fastened thereto. For this purpose the nipple 28 carries a shank 29 adapted to be inserted through the central opening of the cap and extending through the central opening of a flanged hub 30, which hub passes through the central opening of the bearing 31 in the lug carrying arm. The central opening of the cap 21 has a notched edge 32 as is also shown in Fig. 14, these notches and the notches 33 in the hub 30 corresponding so that the shank 29 on the nipple may be staked and pressed into the serrations as shown in Fig. 6. Thus, the nipple and hub 30 are locked in the cap against rotation but the lug carrying arm 27 is free to be rotated within the cap, the lug 26 being preferably a pair of projecting elements adapted to snap into the perforation 34 in the skirt 20 so that the locking lug may be circumferentially adjusted into any one of a plurality of positions. By means of this adjustment the shell and cap may be positioned in any one of many relative adjustments. In order to rotate the lug carrying arm into the desired position a screw driver or similar tool is inserted at the point 35 (Fig. 6) between the lug and cap and the lug pushed away from the cap so as to be clear of the perforations 34, at which time the lug may be rotated into the desired position and permitted to snap back into the proper perforations. An insulated lining 36 is provided in the cap being preferably the usual fiber lining which in the present case is snapped into the position back of the lugs 37, 38 which are pressed out by the wall of the lug carrying arm. Thus the fiber lining is maintained in position and rotated with the lug carrying arm but maintains the cap suitably insulated from the socket.

In assembling the cap and shell of the form shown in Figs. 1 to 9, the edge 24 of the collapsible end of the shell is simply placed inside the open end of the cap skirt 20, the slot 16 being first placed opposite the

locking lug 26. The cap and shell are now telescopically pressed together, the shell collapsing, and as the shoulder 23 on the conical band of the shell passes the edge 22 of the cap skirt, the shell again expands and the band 19 snaps into the recess of the skirt. It is not necessary that the locking lug and shell slot line up when the parts are placed together because they snap together whether they are lined up or not and if not lined up the shell is simply rotated in the cap until the edges 17 of the slot register with the lug 26, at which time the shell fully expands into locking position. It is thus held against rotary adjustment and because of the co-operation between the locking lug 26 and the edges 17 of the slot the shell and cap cannot be separated by a direct longitudinal pull on account of the lug preventing a collapse of the shell. In order to separate the parts the shell is first collapsed by pressing at either of the sides 39 until the corresponding edge 17 is clear of the lug 26, after which a slight rotary adjustment is given to the shell so that the inwardly pressed side of the slot rests against the inner face of the lug 26. The shell is thus partly collapsed and may be separated from the cap by a direct longitudinal pull.

Figs. 10 to 15.

Referring now to the form of my invention as shown in Figs. 10 to 15, it differs from the form already described in that the cap and shell have but one position of assembly. That is, in the present form I do not provide an adjustable locking lug but simply depress portions of the metal at 40 and 41 of the cap 44 (Fig. 14), these depressions acting the same as the lug 26 in that they coöperate with the edges of the slot in the shell to prevent its collapse. In this form of my invention the hub 29 on the nipple 28 is inserted through the central opening in the cap and through a washer 42 (Fig. 15), being then staked so that the nipple is locked against rotation in the cap. In order to hold the insulating lining 36 in the single position cap 44, a pair of ears 45, 46 (Fig. 11) are pressed inwardly from the cap so as to hold the lining in place.

In this form of my invention, that is as shown in Figs. 10 to 15 the same shell 15 may be used as in the first form described, the conical band on this shell and the recessed skirt 20 on the cap 44 being the same shape in both forms. In assembling and separating the parts the operation is the same as described in connection with the first form of my invention.

For the purpose of illustrating my invention I have shown several preferred forms but I understand that changes and modifications will readily occur to those skilled in the art and therefore I do not de-

sire to be limited to the exact forms of my invention as shown and described, but aim to cover all that comes within the spirit and scope of the appended claims.

5 What I claim as new and desire to secure by Letters Patent is:

1. A device of the character described comprising a cap having a conically recessed skirt, a shell having a slotted collapsible end

10 adapted to be telescopically inserted into the recess of the skirt, and an inwardly projecting circularly adjustable lug carried by the cap for engagement with the sides of the shell slot to prevent separation of the 15 cap and shell.

2. A device of the character described comprising a cap having a circularly recessed skirt, a nipple for the cap, a shell having a collapsible slotted end adapted to 20 be telescopically inserted into the recess of the skirt, a lug for engagement with the slot to prevent separation of the cap and shell, and a lug carrying arm rotatably and permanently mounted between the nipple and 25 the cap.

3. A device of the character described comprising a cap having a recessed skirt, a shell having a collapsible conical end adapted to be telescopically inserted into the recess of the skirt, and a circularly adjustable lug carried by the cap for engagement with a slot in the shell to prevent separation of the cap and shell.

4. A device of the character described comprising a cap having a conical circularly recessed skirt, a shell having a telescopic end provided with means to engage within the recess of the cap, and a circularly adjustable lug carried by the cap for 30 engagement with a slot in the shell to prevent separation of the cap and shell.

5. A device of the character described comprising a cap having a conical circularly recessed skirt, a collapsible shell having a telescopic end conforming to the recess of the skirt and adapted to lock therein, and a circularly adjustable lug carried by the cap for engagement with a slot in the shell to prevent separation of the cap and 45 shell.

6. A device of the character described comprising a cap having a conical skirt with turned-in edge, a telescopic shell having a shouldered conical band conforming to the 50 conical skirt and adapted to lock therein, and a circularly adjustable lug carried by the cap for engagement with a slot in the shell to prevent separation of the cap and shell.

7. A device of the character described 60 comprising a cap having a conical circularly recessed skirt, and a collapsible shell having a telescopic end conforming to the recess of the skirt and adapted to lock therein and circularly adjustable means adapted 65 to be placed at points around the cap to prevent relative longitudinal and rotary movement of the cap and shell.

8. A device of the character described 70 comprising a cap having a conical circularly recessed skirt, and a collapsible shell having a telescopic end conforming to the recess of the skirt and adapted to lock therein and a circularly projecting means adapted 75 to be placed at points around the cap to prevent relative longitudinal and rotary movement of the cap and shell.

9. A device of the character described comprising a cap having a conically recessed skirt, a shell having a collapsible end adapted 80 to be telescopically inserted into the recess of the skirt, and a circularly adjustable lug coöperative with the shell to prevent collapse and relative rotation of the cap and shell.

10. A device of the character described comprising a cap having a conically recessed skirt, a shell having a collapsible end adapted to be telescopically inserted into the recess of the skirt, and a circularly adjustable 90 lug coöperative with the shell to prevent collapse and telescopic separation of the cap and shell.

11. A device of the character described comprising a cap having a conically recessed skirt, a shell having a collapsible end adapted to be telescopically inserted into the recess of the skirt, and a circularly adjustable lug coöperative with the shell to prevent collapse and relative rotation of the cap 100 and shell and telescopic separation thereof.

12. A device of the character described comprising a cap having a conically recessed skirt, a shell having a collapsible end adapted to be telescopically inserted into the recess of the skirt, an arm rotatably carried by the cap, a lug carried by the arm coöperative with the shell to prevent relative movement of the cap and shell, and means movable with the arm for engagement with circumferentially disposed perforations in the cap to hold the lug in a predetermined position on the cap.

In witness whereof, I hereunto subscribe my name this 7th day of September, A. D., 115 1918.

VICTOR R. DESPARD.
